UNITED STATES PATENT OFFICE

MAX OBERDORFER AND JOSEF E. RYBERG, OF ST. HELENS, OREGON
COMBINED LIGHT AND HEAVY WEIGHT PAPER MAKING MACHINE

Application filed March 12, 1932. Serial No. 598,361.

Our invention relates to an improvement in paper making machines comprising wet presses and felts as at present arranged.

Heretofore it required two different machines for making light weight and heavy weight papers. In other words, a machine designed for making heavy weight paper sheet required a different arrangement of its elements than the machine intended for making light weight paper sheet, because the web of paper in the one instance required different handling than in the other.

The object of our invention is to provide a single machine adapted for making on it either heavy or light weight paper sheets.

The elements and their arrangement in our machine, by which we attain the objects of our invention, are illustrated in the accompanying drawing constituting a part of this specification.

Such drawing shows diagrammatically the combination of elements composing our machine sufficiently to enable anyone versed in the art of paper making to understand the nature of our invention.

Describing first the combination of elements which are used to make a light weight sheet:

a and *b* represent respectively the couch press rolls; *c* represents the Fourdrinier wire; *d* the pick-up or top felt; *e* and *f* represent the first press rolls; and *i* and *j* represent the transfer press-rolls.

The drier section *k* of our machine is the same whether our machine is to be used for making a light weight paper sheet or a heavy weight paper sheet.

In order to adapt our machine for making on it also a heavy weight paper sheet, we combine with the elements above described, a second pair of press rolls *g*, *h*.

We will first describe the operation of our machine for making a light weight paper sheet.

The light weight paper web is picked up by the pick-up or top felt *d*, as soon as the web has passed thru the couch press rolls *a* and *b*. The paper sheet clings by adhesion to the underside of the pick-up or top felt *d*, as is well understood, and is thus carried to and

thru the first press rolls *e*, *f* and from there the paper sheet is still carried by adhesion on the underside of the pick-up or top felt *d* to the transfer rolls *i*, *j*. At the latter point the paper sheet leaves said top felt *d* and clings to the bottom transfer press roll *i*, and from thence is carried to the drier section *k*. Meanwhile the pick-up or top felt *d* is led around the top transfer press roll *j* back to the couch press rolls *a* and *b*.

In order to prevent the breaking of a light weight sheet it is necessary to extend the top felt *d* from the first press rolls *e*, *f* direct to the transfer press rolls *i*, *j*. The described course of the light weight paper sheet thru the machine is indicated by the arrows *x*.

The course of a paper web forming a heavy weight sheet is indicated by the arrows *y*.

The heavier paper web initially clings to the underside of the pick-up or top felt *d*, and is carried by adhesion to such felt to and thru the first press rolls *e*, *f*.

In passing thru these press rolls the paper web has had squeezed out of it a considerable quantity of its moisture; in short, it is now much drier and much less adhesive; and besides it is also firmer and heavier. In consequence, when the paper sheet has passed thru the first press rolls *e*, *f*, it leaves the pick-up or top felt *d*, and is then led over the roll *l* on the lower felt *n* and on this to the second set of press rolls *g*, *h*; and after passing thru the latter the sheet is conducted direct to the drier section *k*.

Answering in advance a question which may arise in considering the utility of our above described invention, namely:

Could not the top felt *d* be run between the second set of press rolls *g*, *h* and thus serve to carry both light and heavy felts?

Such arrangement would not be practical for making either a light weight sheet or a heavier weight sheet. If used for making a light weight sheet the second press rolls would tend to remove such an additional amount of water from the sheet as to make it too dry to cling to the top felt. Besides, particles of air are entrapped between the top felt and the paper sheet and could not escape, therefore accumulate to such an ex-

tent between the top felt and the paper sheet as to form air blisters which shortly break and cause the sheet to break. To avoid such result, the top felt must be run from the 5 first press rolls *e*, *f* direct to the transfer press rolls *i*, *j*, as mentioned.

A heavier sheet of paper, on the other hand must be run thru a second set of press rolls, as *g*, *h*, to give it the desired density. If the 10 heavier sheet were to be carried by the top felt to the transfer rolls *i* and *j*, after it had passed thru the second press rolls *g* and *h*, it would not only tend to fall off the top felt, but besides, the particles of air which 15 are entrapped between the dense top-felt and the heavier sheet of paper would accumulate and form air blisters breaking thru the sheet in a few seconds and cause it to break.

We claim:

- 20 1. In a paper making machine, the combination with couch rolls, press rolls, transfer rolls and a drier section, and a top felt passing thru said couch rolls and press rolls and then returning over said transfer rolls, 25 of second press rolls located between the first mentioned press rolls and the drier section, said transfer rolls being located to arrange the path of travel of said top felt above said second press rolls.
- 30 2. In a paper making machine, the combination with couch rolls, press rolls, transfer rolls and a drier section, and a top felt passing thru said couch rolls and press rolls and then returning over said transfer rolls, of 35 second press rolls located between the first mentioned press rolls and said transfer rolls, said transfer rolls being located to arrange the path of travel of said top felt above said second press rolls.
